Primary Examiner — Karen E. Eldridge Powers*Assistant Examiner* — Jasmine Mlinarcik(74) Attorney, Agent, or Firm — Edmonds & Cmaidalka(57) CLAIM

The ornamental design for a head cover with gathered scarf, as shown and described.

DESCRIPTION

FIG. 1 is a top front perspective view of a head cover with gathered scarf;

FIG. 2 is a rear elevation view thereof;

FIG. 3 is a left side elevation view thereof;

FIG. 4 is a right side perspective view thereof; and,

FIG. 5 is a rear perspective view thereof.

The broken lines in the drawings represent environmental structure that form no part of the claimed design.
